[57] ABSTRACT

Novel compositions containing as the active ingredient certain steroids containing an oxa or aza side chain at the 17-position possess anti-hyperadreno =corticism activity as evidenced by their ability to inhibit the side-chain cleavage of cholesterol, a key step in the conversion of cholesterol to adrenal hormones.

3 Claims, No Drawings

17-(ARALKYLAMINOALKYL)ANDROSTAN-3B-
OLS, 5 DERIVATIVES THEREOF, ETHERS AND
ESTERS CORRESPONDING

The invention described herein was made in the course of work under a grant or award from the Department of Health, Education, and Welfare.

The present invention is concerned with novel compositions and methods adapted to the treatment of disease states stemming from hyperadrenocorticism. These novel compositions contain, as the active ingredient, a compound of the formula

wherein R is hydrogen or an alkyl or acyl group, R' is an alkyl or aralkyl side chain containing either one or two oxygen or nitrogen atoms, and the dotted line represents an optional 5,6-double bond. Equivalent to the amines encompassed by the foregoing formula are the corresponding pharmaceutically acceptable non-toxic acid addition and quaternary salts as typified by the citrate, tartrate, maleate, ascorbate, gluconate, lactate, succinate, phosphate, sulfate, hydrobromide, hydrochloride, metho-bromide, methochloride, methosulfate, ethosulfate, etc.

A preferred embodiment of this invention comprises compositions containing compounds of the following formula

wherein R is as defined hereinbefore and the dotted line represents an optional 5,6-double bond.

An especially preferred embodiment of this invention comprises compositions containing compounds of the foregoing formula wherein R' is a

and the dotted line represents an optional 5,6-double bond.

A most especially preferred embodiment of this invention comprises the compositions containing compounds wherein R' is a

radical and there is present a 5,6-double bond.

An additional preferred embodiment of this invention is the method of administering to mammals a composition as defined hereinbefore for the purpose of treating disease states resulting from hyperfunctioning adrenal glands.

In the foregoing formulas the alkyl groups are typified by those containing one-18 carbon atoms, while the acyl groups are represented by the following formula

wherein alkyl is as defined hereinbefore. The aralkyl radicals denoted above are typified by the formula

wherein Alk is a bivalent alkylene radical containing one-18 carbon atoms and Ar represents an aryl radical as exemplified by phenyl, tolyl, xylyl, naphthyl and the ring-substituted derivatives thereof.

The compositions and methods of this invention are useful in view of their anti-hyperadrenocorticism activity as evidenced by their ability to inhibit the side-chain cleavage of cholesterol, a key step in the conversion of cholesterol to adrenal hormones.

In mammals the adrenal glands are composed of two distinct parts, the cortex and the medulla. It is thought that the salt- and water-regulating hormones of the adrenals are produced in the outer zone of the cortex, i.e., the zona glomerulosa. The cholesterol content of the adrenal cortex is normally very high. The adrenal cortex is primarily concerned with the maintenance of homeostasis, the tendency toward stability in the normal body states of the organism. A large number of steroids are produced in the adrenal cortex, but the most important are hydrocortisone, corticosterone and aldosterone. Also formed are smaller quantities of estrogens, progesterone and weakly active androgens such as dehydroisoandosterone. The primary activity of aldosterone is the regulation of electrolyte and water changes; it is thus called a mineralocorticoid. Hydrocortisone, on the other hand, regulates metabolic and tissue effects not associated with water and electrolyte balance; thus is called a glucocorticoid. The conversion of cholesterol in the adrenal cortex to the various steroid hormones produced therein is achieved by the action of a number of hydroxylating enzyme systems. Thus, cholesterol is first hydroxylated at the 20 or 22 position and those intermediates are further hydroxylated to afford 20,22-dihydroxycholesterol. Cleavage of that glycol by mitochondrial desmolase results in pregnenolone, which is then hydroxylated at various positions in the molecule to produce hormones such as hydrocortisone, aldosterone, corticosterone, testosterone and estradiol.

Various disease states involve hyperadrenocorticoid activity. Thus, Cushing's syndrome results from an overproduction of hydrocortisone by the adrenal cortex. Primary aldosteronism is the result of the overproduction of aldosterone by the adrenal cortex. Overproduction of androgens, usually the result of an enzymatic defect in the biosynthesis of hydrocortisone, is characteristic of congenital adrenal hyperplasia. Virilization is the most prominent feature of this disorder.

The present invention utilizes compositions which interferes with the formation of adrenal hormones by inhibiting the side-chain cleavage of cholesterol. Numer-

ous agents have been found to inhibit one or more of the steps in the biosynthesis of adrenocortical hormones. This subject is discussed by Temple and Liddle, Ann. Rev. Pharmac., 10, 199 (1970). One such agent which has been studied extensively is aminoglutethimide. That substance has been shown to inhibit the conversion of cholesterol to 20α -hydroxycholesterol. Adrenal inhibitors may be used also as diagnostic agents. It has thus been found that aminoglutethimide reduced the aldosterone secretion rate in patients with primary aldosteronism. This property could thus be used to establish whether or not there would be a beneficial effect from surgical removal of the adrenal glands. The use of aminoglutethimide as a therapeutic agent is, however, severely limited by side effects such as ataxia, anorexia and somnolence. Reversible non-toxic goiters have also been reported in some cases.

The ability of the instant compositions to inhibit the side-chain cleavage of cholesterol is demonstrated by their activity in the assay described by C. H. Doering, Methods in Enzymology, Volume XV, page 591, Academic Press, New York (1969). That assay depends upon inhibition of the enzymatic action of the myto-

20-aminopregn-	100	20.4
5-en-3 β -ol	10	0
22-oxonor-	100	80.0
cholesterol	10	21.4
aminoglutethimide	100	40.2
pregnenolone	100	29.4

The cholesterol side chain cleavage inhibitory activity of the instant compositions is illustrated further by the reduction in blood corticosterone levels following administration to rats of the representative compound, 22-azacholesterol. In that assay five female rats, weighing 160-180 g., are treated intraperitoneally with 5 mg. of 22-azacholesterol in 0.375 ml. of an emulsion prepared from 10 ml. of isopropyl myristate, 20 ml. of saline and 1 g. of Tween 80, daily for a period of 10 days. A similar group of five control animals is treated in the same way with the vehicle alone. The plasma corticosterone levels are measured by the competitive protein binding assay described by Murphy and Pattee, J. Clin. Endocr., 24, 919 (1964). Included in the following table for comparison purposes is data obtained for rats treated with aminoglutethimide, as reported by Gaunt et al., Endocrinol., 87, 1088 (1970).

TABLE II

Compound	Dose	Blood Corticosterone Level		Percent Decrease
		Control	Treated	
22-aza=cholesterol	5 mg. each day for 10 days	500 ng/ml (mean) 375 ng/ml (median)	230 ng/ml (mean) 187.5 ng/ml (median)	54
				50
aminoglu=tethimide	100 mg/kg/day	713 ng/ml	275 ng/ml	72.4
	50 mg/kg/day	185 ng/ml	139 ng/ml	24.9

chondrial fraction of bovine adrenal cortex on cholesterol- 7α - ^{3} H,26- ^{14} C. The loss by volatilization of one of the cleavage products, i.e., isocaproic acid- ^{14} C, seen as a change in isotope ratios, is a direct measure of enzymatic activity, thus of side-chain cleavage. In that assay the results shown in the following table are obtained.

TABLE I

Compound	Concentration (μ M)	Percent inhibition
20-azacholesterol	100	79.1
	10	34.5

	10	30.0

The instant compositions can be administered in a dose range of about 1-1,000 mg/day. From the foregoing in vitro and in vivo data it is estimated that 22-azacholesterol is about 10 times as potent as aminoglutethimide, thus should be administered at a preferred dose of about 100 mg./day.

The novel anti-hyperadrenocorticism compositions of this invention comprise one of the aforementioned active ingredients combined with a pharmaceutically acceptable carrier. These compositions can be administered either orally or parenterally. For oral administration tablets, lozenges, capsules, dragees, pills or powders are suitable, while aqueous solutions, non-aqueous solutions or suspensions are appropriate for parenteral administration. Acceptable pharmaceutical carriers are exemplified by gelatin capsules, sugars such as lactose or sucrose, starches such as corn starch or potato starch, cellulose derivatives such as sodium carboxymethyl cellulose, ethyl cellulose, methyl cellulose or cellulose acetate phthalate, gelatin, talc, calcium phosphate such as dicalcium phosphate or tricalcium phosphate, sodium sulfate, calcium sulfate, polyvinylpyrrolidone, acacia, polyvinyl alcohol, stearic acid, alkaline earth metal stearates such as magnesium stearate, vegetable oils such as peanut oil, cottonseed oil, sesame oil, olive oil, corn oil or theobroma, water, agar, alginic acid, benzyl alcohol, isotonic saline and phosphate buffer solutions as well as other non-toxic compatible substances used in pharmaceutical formulations.

The instant method for producing an anti-hyperadrenocorticism response in mammals comprises administration of an instant novel composition contain-

ing a therapeutically effective amount of the active ingredient. The term "therapeutically effective amount" is defined as the amount of active ingredient that will produce an anti-hyperadrenocorticism effect. For a particular subject the actual amount of active ingredient to be used will vary with the nature of the subject, the severity of the disease state, the route of administration and the particular active ingredient used.

The preparation of a representative composition suitable for oral administration is described as follows.

55 g. of 22-azacholesterol is sifted through a number 30 mesh screen, then is combined with 4,440 g. of terra alba, 937 g. of corn starch U.S.P. and 222 g. of polyvinylpyrrolidone. Those ingredients are mixed, then are moistened with 200 ml. of isopropyl alcohol and the mixture is comminuted, then granulated with 1,100 ml. of isopropyl alcohol. That mixture is comminuted and dried at 140° F. for 4 hours. 62 g. of magnesium stearate is added and the mixture is extruded through a 9.52 mm. dye to afford 20,000 tablets, each containing 25 mg. of 22-azacholesterol.

The compounds used in the novel compositions of this invention are manufactured by various methods which are well known in the art. For example, compounds with an oxa and oxa-aza side chain can be produced by methods described by Irmischer et al. in *Stroids*, 7, 557 (1966).

The compounds with aza side chains may be prepared by treating the appropriate amine with the appropriate ketone or aldehyde and then reducing the product with a reducing agent such as sodium borohydride to afford the desired aza derivatives. Typically, 20 α -aminopregn-5-en-3 β -ol is refluxed with isobutyl aldehyde in methanol and the product reduced with sodium borohydride to yield 20 α -isobutylaminopregn-5-en-3 β -ol.

Alternatively, an appropriate amine may be acylated with an appropriate acid chloride to yield the amide. Then the amide is contacted with a reducing agent such as lithium aluminum hydride to yield the amine. The above reaction sequence is illustrated by the treatment of 20 α -aminopregn-5-en-3 β -ol 3-tetrahydropyranyl ether with 4-methylvaleryl chloride to yield the crude amide. Reduction of the amide with lithium aluminum hydride affords 20 α -isohexylaminopregn-5-en-3 β -ol.

The methods of preparation of the compounds employed in this invention will appear more fully from the examples which follow. In those examples temperatures are given in degrees Centigrade (°C.) and quantities of material in parts by weight unless parts by volume is specified.

EXAMPLE 1

A solution of 0.500 part of 20 α -aminopregn-5-en-3 β -ol and three parts of isobutyl aldehyde in 40 parts of absolute methanol is refluxed for 2 hours on a steam bath. Then the reaction mixture is allowed to cool to room temperature and three parts of sodium borohydride is added to the stirred mixture, portionwise over a 30 minute period, at a temperature of about 10°-20°. After that addition is completed, stirring is continued for an additional 2 hours. Then eight parts of acetone is added to destroy the excess sodium borohydride and the reaction mixture is poured into ice water. The precipitate which forms is collected by filtration, washed with water and allowed to dry. Recrystallization of the crude product from acetone-water affords pure 20 α -

isobutylaminopregn-5-en-3 β -ol (22 α -azanorcholesterol), melting at about 128°-130° and displaying an optical rotation of about -34.5°.

EXAMPLE 2

Substitution of equivalent quantities of formaldehyde, acetaldehyde, dimethyl ketone and isoamyl-aldehyde in the procedure of Example 1, affords, respectively, 20 α -methylaminopregn-5-en-3 β -ol, 20 α -ethylaminopregn-5-en-3 β -ol, 20 α -isopropylaminopregn-5-en-3 β -ol and 20 α -isoamylaminopregn-5-en-3 β -ol.

EXAMPLE 3

To a stirred solution of 0.500 part of 20 α -aminopregn-5-en-3 β -ol 3-tetrahydropyranyl ether in 17.6 parts of benzene is added dropwise a solution of 0.840 part of 4-methylvaleryl chloride in 8.8 parts of benzene. The mixture is stirred at room temperature for 24 hours and then is poured into ice water. The organic phase is separated, washed successively with water and 5 percent sodium bicarbonate solution, dried over anhydrous sodium sulfate and filtered. The filtrate is evaporated under reduced pressure to afford the crude amide. Then 0.60 part of the crude amide is dissolved in 26 parts of hot dioxane and that solution is added dropwise to a refluxing slurry comprised of 0.500 part of lithium aluminum hydride in 78 parts of dioxane. The mixture is refluxed and stirred for 20 hours whereupon the excess hydride is decomposed by the successive dropwise addition of 40 parts by volume of a 1:4 water-dioxane solution, five parts by volume of a 25 percent sodium hydroxide solution and five parts of water. The mixture is filtered to remove the inorganic salts, which are washed on the filter with dioxane, and then the filtrate is evaporated to dryness. The remaining material is dissolved in ether and hydrogen chloride gas is added to the solution. The hydrochloride salt which precipitates is collected by filtration and treated with potassium carbonate to afford crude product. Recrystallization of the crude product from acetone affords pure crystalline 20 α -isohexylaminopregn-5-en-3 β -ol, melting at about 113°-114° and displaying an optical rotation of about -26.6°.

EXAMPLE 4

When an equivalent quantity of 3-phenylpropionyl chloride is substituted in the procedure of Example 3, there is produced 20 α -(3-phenylpropyl)aminopregn-5-en-3 β -ol.

EXAMPLE 5

Substitution of an equivalent quantity of phenylacetyl chloride in the procedure of Example 3 affords 20 α -phenethylaminopregn-5-en-3 β -ol.

EXAMPLE 6

By substituting equivalent quantities of 20 α -aminopregn-3 β -ol 3-acetate and 3-phenylpropionyl chloride in the procedure of Example 3, there is produced 20 α -(3-phenylpropyl)aminopregn-3 β -ol 3-acetate.

EXAMPLE 7

Substitution of equivalent quantities of 20 α -aminopregn-3 β -ol 3-methyl ether and 3-phenylpropionyl chloride in the procedure of Example 3 affords 20 α -(3-phenylpropyl)aminopregn-3 β -ol 3-methyl ether.

EXAMPLE 8

When equivalent quantities of 20α -aminopregnan-3 β -ol 3-propionate and 3-phenylpropionyl chloride are substituted in the procedure of Example 3, there is produced 20α -(3-phenylpropyl)aminopregnan-3 β -ol 3-propionate.

EXAMPLE 9

Substitution of equivalent quantities of 20α -aminopregn-5-en-3 β -ol 3-acetate and 3-phenylpropionyl chloride in the procedure of Example 3, yields 20α -(3-phenylpropyl)aminopregn-5-en-3 β -ol 3-acetate.

What is claimed is:

1. A compound of the formula

wherein R is hydrogen or an alkyl or alkanoyl radical containing one to three carbon atoms, Alk represents an alkylene radical containing two to three carbon atoms and the dotted line indicates an optional 5,6-double bond.

2. As in claim 1, a compound of the formula
